UNITED STATES PATENT OFFICE

2,048,431

OVEN EQUIPMENT

William A. Darrah, Chicago, Ill.

Application November 11, 1933, Serial No. 697,587

3 Claims. (Cl. 107—59)

This invention relates to ovens, furnaces, dryers and similar equipment in which it is desired to maintain a set of conditions in a closed chamber and to keep said chamber from having a full contact with the surrounding atmosphere. Some of the objects of my invention are to provide a structure which may be readily loaded or unloaded while maintaining the interior of the structure substantially closed from contact with the surrounding atmosphere.

Further objects of my invention are to provide means for economizing fuel in those cases in which the structure is heated. Other objects of my invention are to provide more endurable conditions for workmen operating the equipment and to prevent the loss of vapor or gases from the interior of my structure. Further objects of my invention provide control of heat distribution within the structure.

Other objects of my invention will be apparent from the drawing, description and claims attached hereto.

In the accompanying drawing:—

Figure 1 shows a front elevation partly broken away of one form of my device, while

Figure 2 shows a side elevation also partly broken away of the same device.

1 indicates a housing or structure which may be formed of brick, tile or if desired of steel and insulated in order to retain the difference of temperature between the inside and outside of my equipment. The structure 1 is provided with a roof 2 which for ease of construction I have shown arched and two fire boxes or combustion chambers 3 and 4. The fire boxes are provided with a burner member 5 which may be adaptable for oil, gas, powdered coal, etc. and cooperates with a combustion block 6. Combustion takes place within the interior of lining 7 which is formed from refractory materials and which is spaced away from the bottom walls 8 of oven member 1 by an air space 9, allowing circulation of the atmosphere within the oven substantially entirely around combustion lining 7. A

flue member 10 conducts the products of combustion from lining 7 toward the rear portion of housing 1 and discharges them through an outlet 11 into the interior of the oven which is indicated by 12. The structure is provided with an opening 13 which may be used for loading or unloading, etc. A hood 14 is placed adjacent to opening 13 and connects to a stack or exhaust duct 15 at its upper portion. An exhaust duct 16 in the oven structure 1 provides means by which the products of combustion can leave the structure to make room for the additional new products of combustion.

Flue or duct 16 is provided with a damper 17 which serves to control the rate of travel of gases through duct 16. I have shown duct 16

connecting into stack member 15, but it will be understood that this is a matter of convenience as the exact arrangement of duct 16 is a matter which may be varied to a considerable extent.

Structure 1 is provided with a conveyor device 18 which serves to move the material being treated through enclosure 12. For purposes of convenience I have shown conveyor member 18 as consisting of a reel in which a central shaft 19 carried in bearings 20 and 21 serves to support the moving structure. It should be understood that I do not wish to confine my invention to the particular type of conveyor shown as obviously chain or apron conveyors, and many other types, may be used interchangeably with departing from the principles which I am here disclosing. Shaft 19 is provided with a sprocket 22 which is driven by chain 23 from a motor 24 or other desired source of power. Shaft 19 is provided with a series of arms as illustrated by 25, the arms being supported by a hub member 26. The arm members such as 25 are grouped in pairs as illustrated in Figure 1 by 25 and 25A. A tray or plate 27 is suspended from the arms by means of a link member 28 which pivots on member 29, so that the tray 27 always remains in a substantially horizontal position, independently of the position of the arms. It will be understood therefore that as the arms rotate in the direction shown by the arrow in Figure 2, the trays or plates 27 are loaded, as they come opposite opening 13 and then travel downward around shaft 19 describing an irregular figure which approximates an ellipse. As the trays complete the revolution and return to opening 13 they are in turn unloaded and a new load of raw material placed on them. This type of equipment may obviously be used, for baking, drying, etc. of various materials such as chemicals, blocks, food stuffs, crackers, bread, etc.

In order to prevent a rapid circulation of the atmosphere within the oven upward and outward through opening 13, various means are provided. A baffle member 30 extends from a point near opening 13 downward to a point beneath the conveyor mechanism 18 and serves to make the travel of products of combustion out of opening 13 difficult. Inner baffle member 31 is mounted upon shaft 19 in such a manner as to remain substantially stationary while the shaft 19 and conveyor mechanism 18 revolves. Baffle 31 may be supported in a great variety of ways to accomplish this result but for convenience I have shown baffle 31 carried on a frame indicated by 32 which is supported from saddles or bearings 33 and 34, which rest on shaft 19. I prefer to form the outer contour of baffle 31 in such a shape that it presents at all times a certain minimum clearance between the nearest point of

tray members 27 and the outer wall of baffle 31. It will be apparent therefore that under these conditions, the combination of the tray member 27, the baffle 31 and the walls of the structure 1 5 form a rough sealing arrangement such that products of combustion can only with difficulty pass outward through opening 13.

It will be apparent that baffle member 31 also contributes greatly to the sealing effect in the 10 lower portion of the structure 1.

In order to still further reduce the volume of gases which can pass through openings 13, I provide a series of pivoted sealing members as indicated by 33A, 34A, 35 and 36. In one practical form, these devices consist of long strips of sheet metal extending substantially from end to end of chamber 1. These devices may be pivoted as for example at 31 and provided with a counter-weight as 38, which is arranged to keep 15 the sealing members pressed into contact with the tray members. It will be apparent that the size and arrangement of weight members 38 is chosen such as to provide a firm, but yielding pressure. Obviously in place of the weights 38, 20 I may employ a spring or I may use the weight of the sealing member itself to accomplish the desired result. On examining Figure 2, it will be noted that the space within the structure 1 which 25 communicates with opening 13 is closely sealed on all sides, so that for practical purposes it may be stated that there is no flow of gases either inward 30 or outward through opening 13.

In this connection it may be pointed out that 35 it is in many cases as desirable to prevent the inward flow of cold air from a room into the oven structure, as it is to prevent the outward flow of hot products of combustion. Either condition represents a waste of heat and is likely to cause other difficulties. For example, an inward flow 40 of cold air will chill the products being baked and may radically disturb the humidity content of the gases in the oven. In the same manner an outward leakage of hot gases from within the oven through opening 13 may cause a considerable loss of heat and may make the working conditions about the oven so difficult that loading 45 and unloading becomes slow, expensive and uncertain.

In the case illustrated by the drawing, a floor 50 or platform 39 is shown at a convenient elevation for the workmen to stand when operating the oven.

From a thermal standpoint, it will be apparent 55 that the heat is produced in the lower forward corner of the structure and a considerable portion radiated upward to the lower front half of conveyor member 18. The bulk of the products of combustion, however, travel through flue 60 11 toward the rear portion of structure 1 then upward over the top and leave by the duct 16 in the forward portion of the oven. It will be apparent therefore that the flow of heat is around substantially the entire circumference of the oven, the heat being removed at a point a considerable distance away from its point of generation. 65 This results in a good distribution of heat and a relatively high thermal efficiency.

I have found that ovens without the features 70 of my invention consume a much greater amount of fuel and give less satisfactory heating conditions. It is also a well known fact that ovens of this type are very difficult to operate particularly during warm seasons, owing to the large out 75 flow of heat through the charging opening.

My invention therefore results among other things, in obtaining a materially improved heat economy, a superior heat application and distribution, better working conditions, control of humidity conditions, etc.

It will be understood that many changes in size, shape and arrangement of the mechanical parts of my equipment may be made without departing from the spirit of my invention.

It will be understood that the combustion 10 chamber may be arranged so that the desired amount of radiant heat can be liberated from the surface of said combustion chamber to the exposed portion of the work carrying devices while the products of combustion travel along the flue 15 leading from said combustion chamber and are exhausted into the oven at a point a considerable distance away from said combustion chamber, the point of exhaust being subject to control by means of damper 41 which may be moved over a 20 series of openings indicated by 40 in said flue 11. The position of damper 41 may be controlled by rod 42, which serves to slide damper 41 backward and forward as desired. In a similar manner a 25 shield 43 is provided above combustion chamber 7 and arranged to be rotated by means of rod 44 so as to control the amount of radiant heat leaving the surface of combustion chamber 7 and passing to the material being baked.

This arrangement it will be noted gives control 30 both of the distribution and relative quantity of radiant heat and convected heat from combustion chamber 7 in different portions of the oven.

It should be understood, that by the term oven, 35 I intend to include such structures as dryers, evaporation furnaces, baking and conditioning equipment which come within the scope of my drawing, specification and claims.

Having now fully described my invention, what 40 I claim as new and wish to secure by Letters Patent in the United States, is as follows:

1. An oven consisting of a housing, a reel member mounted therein, a series of work supports pivotally carried by said reel member, a combustion chamber located below said rotating member and provided with and connected to a flue provided with ports for controlling the heat flow therefrom, a system of baffles including a normally stationary centrally located one for 50 directing the travel of hot gases in connection with said rotating member, a working opening and movable sealing members cooperating with said baffles and said work supporting members to prevent passage of gases through said working 55 opening, and means for controlling the distribution of radiant heat to said work supports.

2. In a reel type oven, a housing, a working opening through said housing, a baffle system within said housing, work carrying means arranged to travel through a circular path within said housing and between said baffle means, and sealing members adapted to flexibly maintain contact between said work supporting members and baffles thereby preventing leakage through 65 said working openings.

3. In an oven, a housing, a working opening therethrough, movable work supports therein, baffles directing the flow of heat around said 70 work supports and sealing means arranged to flexibly contact said work supports and baffles to prevent leakage through said work opening.
